United States Patent Office

Des. 222,662
Patented Nov. 30, 1971

222,662

COMBINED BOTTLE AND CLOSURE THEREFOR

Giorgio Fabbri, Via Emilia Ponente 276,
Bologna 40132, Italy

Filed Aug. 7, 1970, Ser. No. 24,375

Claims priority, application Italy May 8, 1970

Term of patent 3½ years

Int. Cl. D9—01

U.S. Cl. D9—1

FIG. 5

FIG. 6

FIG. 1 is a front perspective view of a combined bottle and closure therefor, showing my new design;

FIG. 2 is a rear perspective view;

FIG. 3 is a top plan view on an enlarged scale;

FIG. 4 is a bottom plan view;

FIG. 5 is a front view; and

FIG. 6 is a rear view thereof.

I claim:

The ornamental design for a combined bottle and closure therefor, substantially as shown.
